COOKING UTENSIL

Charles J. Daubenberger, Pacific Palisades, Calif.

Application March 22, 1948, Serial No. 145,262

Term of patent 3½ years

(Cl. D44—1)

To all whom it may concern:

Be it known that I, Charles J. Daubenberger, a citizen of the United States, residing at Pacific Palisades, in the county of Los Angeles and State of California, have invented a new, original, and ornamental Design for a Cooking Utensil, of which the following is a specification, reference being had to the accompanying drawing, forming part thereof, in which:

Fig. 1 is a top plan view of a cooking utensil showing my new design;

Fig. 2 is a side elevational view;

Fig. 3 is a section taken on the broken line 3—3 of Fig. 2; and

Fig. 4 is an end elevational view showing the louvers thereof.

I claim:

The ornamental design for a cooking utensil, as shown.

CHARLES J. DAUBENBERGER.
